MALCOLM H. BAKER, OF BRAINTREE, MASSACHUSETTS; MARIE H. BAKER, ADMINISTRATRIX OF SAID MALCOLM H. BAKER, DECEASED, ASSIGNOR TO KENNETH W. CROSBY, TRUSTEE, OF BOSTON, MASSACHUSETTS.

THERMODYNAMICALLY-CONTROLLED SWITCH.

1,334,211.

Specification of Letters Patent. Patented Mar. 16, 1920.

Application filed September 17, 1915, Serial No. 51,206. Renewed June 11, 1919. Serial No. 303,476.

To all whom it may concern:

Be it known that I, MALCOLM H. BAKER, a citizen of the United States, and a resident of Braintree, in the county of Norfolk and 5 Commonwealth of Massachusetts, have invented certain new and useful Improvements in Thermodynamically-Controlled Switches, of which the following is a specification.

10 My invention relates to electric switches involving in their operating mechanisms thermo-dynamic means for partial automatic control and has for its object, generally, to provide in such switches an ar- 15 rangement of the thermo-dynamic controlling means whereby designed circuit-govern- ing action of the switch may automatically be caused when such means are thermally energized and particularly, but not exclu- 20 sively, when such means are so energized by the electric current.

More specifically, the object is to thermo- 25 dynamically control the relative movement of electrical contacts in such manner that said movement is permitted to occur a pre- 30 determined time after designed energization of the thermo-dynamic controlling means,— or, in other words, to introduce a time element, comprising the operative period of a thermo-dynamic device active to free the contacts for relative movement, between the 35 act of energizing the said device and the actual making or breaking of the circuit.

As a preferred and specific embodiment 40 of my invention, I have illustrated it herein as a time controlled, thermostatically governed, circuit breaking device,—and the particular form of such device that I have chosen for illustrative purposes is a one- way snap switch, of the single pole type, and of a common and well known mechanical arrangement.

My invention may, however, be equally well applied to any other form of switch, 45 such as a blade knife, push button, lamp socket, pendant, cord pull, or magnetically controlled switch, by suitable modification of the operative parts.

It is of course clear that perhaps the most 50 advantageous application of my invention is to switches which control electric lights. In such case the provision of a slight time interval, varying from some ten seconds to

a few minutes after manual extinguishment causing actuation of the switch and before 55 actual cessation of the light, is not only of material convenience, but often an actual safeguard against accidents.

That is, conditions of attainment being 60 equally easy and reliable, a light which involved such continuation would practically always be chosen over one which did not.

My invention accomplishes this result not 65 only in a simple and cheap manner, but in one which is absolutely reliable and durable, commercially.

In carrying out my invention, as specifically illustrated and described herein, I employ the usual "snap" switch,—and I also employ a detent adapted to retain the switch 70 contacts closed after the button has been turned to the "off" position, and other detent means to hold the button at said "off" position after it has been so turned. And I provide a thermo-dynamic device, adapted 75 to be energized by the electric current, to free the said first detent means and permit the opening of the switch contacts after a predetermined time, the said thermo-dynamic device being energized by the act of 80 "turning off" the button.

For operatively energizing the thermo- 85 dynamic device I may use any suitable electrical resistive unit, but I preferably employ a winding of resistance wire arranged in heating relation to said device.

I have illustrated my invention in the annexed drawings, in which Figure 1 is a plan view, with the casing and control button removed and the parts shown in the circuit-broken position. Fig. 2 is a section taken on the parallel planes A—A of Fig. 1 with parts in same relation as therein shown and with the casing and control button appearing. Fig. 3 is a partial plan view, 90 otherwise like Fig. 1 generally but with parts in the circuit-making position. Fig. 4 is a detail perspective view of the shaft and certain allied parts. Fig. 5 a partial section taken on the horizontal plane B—B 100 of Fig. 2, the parts being shown in the intermediate position, or the one assumed after the button has been turned to its circuit-breaking position and while the thermostat is heating. Fig. 6 shows a detail of certain 105 parts taken on the horizontal plane C—C of

Fig. 2, said parts being positioned as in Figs. 1 and 3. Fig. 7 is a view similar to Fig. 3 but showing the intermediate position of parts above referred to. Fig. 8 shows the parts of Fig. 6 positioned correspondingly to Fig. 7; Fig. 9 is a detail view taken in section on the plane D—D in Fig. 8. Fig. 10 is a diagram of electrical connections of the single-pole type of switch illustrated in the above figures; and Fig. 11 is a diagram of electrical connections suitable for a double-pole type of otherwise similar switch wherein the heat generating resistance unit is shown connected in shunt to the switch governed load when the control button is turned for causing delayed opening of the main contacts.

Throughout the several views of the drawings, identical parts are designated by the same reference numerals.

In the drawings, Fig. 1 to 9 inclusive, the button is shown at 1 and the shaft at 2, the latter being guided in bearings 3, 4, mounted upon the porcelain base 5. The shaft also carries, fixed to it, a collar 6 having a notch 7 engaged by one end of a coiled spring 8 the other end of which is attached to a portion 30 of a plate 11 hereinafter described. This shaft also carries a cam 9 adapted to engage a radially sliding dog 10 guided in a recess plate 11 attached to and insulated from contact clips 12, 12. These clips are adapted to engage blades 13, 14, mounted upon the base 5. At the lower end of the shaft 2, below the base 5, is attached a plate 15 arranged to engage, successively, and at diametrically opposite points, a spring pawl 16 mounted upon the base 5. This plate 15 carries, insulated from it, contact clips 17, 17, adapted to engage blades 18, 19, mounted upon the base 5.

A bi-metallic thermostat, arranged with the more expansible metal inside, is shown at 20, and is mounted upon the base 5 by means of the bracket 21. This thermostat carries, at its opposite end from said bracket, a small plate 22 provided with a screw stud 23 engaging one end of a bell crank 25 through a slot therein. This latter lever is pivoted at 26 to the bracket 21, and has, at its other end, a stud 27 fitted with a loose roller 28 adapted to engage, successively, the opposite extensions 29, 29, of the recess plate 11. The thermostat is covered with some suitable material such as asbestos or mica, and is provided with a heating resistance winding 33.

A ratchet 36 is fixed to the bracket 21 and arranged to engage a projection 34 of the sliding dog 10, as later set forth.

Operation is as follows, starting from the circuit-broken position of the switch as shown in Fig. 1,—the button 1 is turned right handed in the usual manner, which rotates the shaft 2 and therewith the cam 9,

the latter causing the dog 10 to slide radially and outwardly until its projection 34 disengages the tooth 35 of the fixed ratchet 36. At the same time the coil spring 8 is placed under tension and thereby snaps the clips 12, 12, into engagement with their blades 13, 14, thus closing the main circuit. Just previous to this, however, the clips 17, 17, have been moved into engagement with their blades 18, 19, thus shunting out the resistance 33.

While these operations have been taking place, the plate 11, as it has turned, has carried with it the dog 10 which, due to its engagement with the cam 9, has retreated to a position at which the projection 34 has engaged the next tooth of the ratchet 36. The engaged relation of this projection 34 with the tooth is shown in Fig. 6 and the disengaged relation in Fig. 8. The relation of the contact clips appears in Fig. 3.

The switch is now closed and operates as a simple single pole switch.

Referring to the diagram of connections in Fig. 10, it is seen that current passes from line 37 through main contacts, here indicated at 38, then by way of wire 39 and auxiliary contacts, indicated at 40, around the resistance 33 and so to the load line 41, the resistance 33 being therefore practically dead.

When it is desired to open the switch, the button is rotated in the same direction until caught and held by the engagement of the plate 15 with the spring pawl 16. The main contacts are held closed by the engagement of the roller 28 with the projection 29 of the plate 11. Thus the coiled spring 8 is held under operative tension, ready to act to break the main contacts when the same are freed. At the same time the rotation of the shaft has opened the auxiliary contacts 17—18, 17—19, thus causing the entire line current to flow through the winding 33, which heats, bends the thermostat, and frees the roller 28 from the projection 29, as shown in broken lines in Fig. 7. The stored energy of the coiled spring now snaps open the main contacts, thus breaking the circuit, both through load and resistance.

The intermediate relation of parts,—i. e. the relation after the button has been turned to its circuit-breaking position but before the main contacts are released to open,—is shown in Fig. 7 and the relation after the said main contacts are opened of course appears in Fig. 1, save that in said figure the thermostat is shown as cooled.

The time element which shall elapse between the turning off of the button and the rupture of the main circuit may readily be varied, with a given load, by altering the size or number of turns of the resistance 33,—the size of the thermostat,—the engagement of the roller 28, etc. Preferably I correlate the parts to operate in about forty five

seconds, but ample adjustment may be had, say from ten seconds to five minutes, as above set forth.

Fig. 11 shows the connections of the switch 5 with the resistance in shunt to the load voltage, the said switch being here preferably of the double pole type, or, at least, of a type carrying both poles of the circuit as required for a shunt connection. I have not 10 thought it needful to specifically illustrate this type as it merely involves the addition of a pair of contacts and a re-arrangement of the relative position of main and auxiliary contacts. Referring to this figure, it is 15 here pointed out that when the two pairs of main contacts are normally closed, the auxiliary contacts 40 which control the circuit through the heating resistance 33, are open, and said resistance therefor deenergized; but that upon movement of the 20 control button to its position for causing automatic opening of the contacts, said auxiliary contacts are manually closed to electrically energize this resistance. It should also 25 be noted that the shunt circuit containing resistance 33 is tapped from the load side of the main contacts so that upon opening of the latter, said resistance is deenergized.

It is evident that when the button 1 is 30 rotated to the "off" position, and while the thermostat is heating to free the switch contacts to separate, the controlling parts including said button are operatively locked against further movement. That is, the operator having once turned the button to the "off" position cannot turn same further, or to the "on" position, again until the switch contacts have opened. In this manner mistakes on the part of users of the switch are prevented, particularly in the case where no visible change is brought about by the movement on the button to the "off" position,—as when no indicator plate is used.

I find that the use of an indicator plate 45 32, placed above the collar 6 in the usual manner, is of advantage as showing the operator that he has actually accomplished the desired purpose by turning the button.

In general, in the snap switch form here- 50 in shown, I find it of advantage to add a plate 42 of suitable insulating material at the bottom of the porcelain base 5 as additional protection, although this may not be essential.

It will be obvious that the operative principles of my broad invention, herein described and claimed, are capable of embodiment in other forms and arrangements of switch mechanisms than the specific examples herein disclosed for illustrative purposes only. Without therefore limiting myself to the precise embodiments of my invention herein shown, what I claim is:—

1. In a two-branch-circuit controlling 65 switch, in combination; master contacts ar-

ranged in series with the two-branch-circuit, a detent positioned normally to maintain said master contacts closed, thermo-dynamic means operatively related to said detent upon thermal energization to release said master contacts therefrom, a heating device in one branch of said two-branch-circuit for said thermo-dynamic means, control means adapted to put said master contacts under tension for automatic opening, auxiliary contacts in the other branch of said two-branch-circuit, and manually controllable means for opening said auxiliary contacts simultaneously with the tensioning of said master contacts, whereby said heating device may be rendered operative thermally to energize the said thermo-dynamic device. 75 80 75

2. In a two-branch-circuit controlling switch, in combination; master contacts arranged in series with the two-branch-circuit, a detent positioned normally to maintain said master contacts closed, thermo-dynamic means operatively related to said detent upon thermal energization to release said master contacts therefrom, a heating device 85 in one branch of said two-branch-circuit for said thermo-dynamic means, auxiliary contacts in the other branch of said two-branch-circuit, manually controllable means for establishing tension tending to open said master contacts and also for operating said auxiliary contacts, whereby said heating device may be rendered operative thermally to energize the said thermo-dynamic device. 90 95

3. In a two-branch-circuit controlling 100 switch, in combination; master contacts arranged in series with the two-branch-circuit, a detent positioned normally to maintain said master contacts closed, thermo-dynamic means operatively related to said detent 105 upon thermal energization to release said master contacts therefrom, a heating device in one branch of said two-branch-circuit for said thermo-dynamic means, auxiliary contacts in the other branch of said two-branch-circuit, and manually-actuated control means 110 arranged upon one actuation to close both said master contacts and said auxiliary contacts, and further arranged upon subsequent actuation to open said auxiliary contacts 115 and to tension said master contacts for the automatic opening thereof.

4. A one-way, rotary snap switch embodying in combination; stationary contact members, a rotary contact device adapted conductively to bridge said members, manually operable means for controlling said device, a resilient connection between said device and said means, detent mechanism arranged cooperatively with said resilient connection 120 to produce a quick, tension-caused, follow-up movement of said device relative to said means, a detent and controlling thermostat therefor positioned normally to retain said device in its contact-bridging position, a 125 130

4
latch arranged automatically to hold said means rotatively advanced and separated from said device against the tension in said resilient connection, and a heating circuit 5 for said thermostat, with connections operative to energize said circuit when said means are so held rotatively separated from said device.

5. A one-way, rotary snap switch embodying in combination; stationary contact members, a rotary contact device adapted conductively to bridge said members, manually operable means for controlling said device, a resilient connection between said device 10 and said means, detent mechanism arranged co-operatively with said resilient connection to produce a quick, tension-caused, follow-up movement of said device relative to said means, a detent and controlling thermostat 15 therefor positioned normally to retain said device in its contact-bridging position, a latch arranged automatically to hold said means rotatively advanced and separated from said device against the tension in said 20 resilient connection, and a heating circuit for said thermostat, with connections operatively to energize said circuit when said means are so held rotatively separated from said device, said connections being further 25 arranged so that said circuit is automatically de-energized by contact opening movement 30 of said device.

6. A one-way, rotary snap switch embodying in combination; stationary contact members, a rotary contact device adapted conductively to bridge said members, manually operable means for controlling said device, a resilient connection between said device and said means, detent mechanism arranged 35 co-operatively with said resilient connection to produce a quick, tension-caused, follow-up movement of said device relative to said means, a detent and controlling thermostat 40 therefor positioned normally to retain said device in its contact-bridging position, a latch arranged automatically to hold said means rotatively advanced and separated from said device against the tension in said 45 resilient connection, and a heating circuit for said thermostat, with connections automatically to establish said circuit solely in series with the switch governed 50 load when said means are so held rotatively separated from said device.

55 7. In an electric switch, in combination; manually controllable device for establishing the main switch contacts in normal closed relation and not tensioned for opening, a detent and controlling thermostat 60 therefor positioned normally to prevent opening of the said contacts, a resilient connection operable by said device to tension said contacts for opening movement, an electrical resistance arranged in heating 65 relation to the thermostat, and circuit con-

nnections governed by said device whereby contact-closing movement of said device establishes a two-path series-parallel connection through the switch, one path thereof containing said resistance and the other path 70 thereof forming a shunt circuit around said resistance; together with means arranged automatically to open said shunt circuit simultaneously with the tensioning of said contacts. 75

8. A snap switch embodying in combination; a rotary contact device, manually controllable means for rotating said device, an auxiliary contact device operably related to said means, a resilient connection between 80 said means and said rotary device, detent mechanism adapted automatically to cause a quick, follow-up movement of said rotary device relative to said means, a latch arranged to arrest said means in a position 85 tensioning said rotary device for circuit breaking movement, a detent and controlling thermostat therefor positioned normally to prevent circuit breaking movement of said rotary device, and a heating circuit for 90 the thermostat, adapted to be energized by movement of said means to its said tensioning position.

9. In a one-way snap switch, in combination with a circuit-governing, spring-actuated rotary contact device, and a thermostat arranged automatically to control the movement thereof, a radially projecting member carried by the said device and a pivoted detent lever having one end thereof 95 adapted to engage with said projection for preventing movement of said device, and having the said thermostat operatively connected to another portion thereof, the said 100 detent lever being pivoted substantially upon 105 a line tangential to the arc of movement of said projecting member.

10. In an electric circuit switch, manually controlled means adapted at one actuation thereof to close the switch and at the 110 next actuation thereof to energize mechanism tending to open the switch, means to retain the said switch closed, means to lock the said controlling means against reverse movement after said second actuation thereof; together 115 with a thermostat to govern the said retaining means, and a heating circuit for the said thermostat, the said heating circuit being energized by the said second actuation of the manual controlling means. 120

11. In a thermostatically governed electric switch, in combination with the contact members having relative movement to open and to close the switch, and a thermostatic detent to restrain said opening movement, 125 controlling means to close the switch and to cause opening of the switch, and means to lock said controlling means in inoperative relation to the switch contacts after said means have been moved to a position adapt- 130

ed to cause opening of the switch and until said switch is opened.

12. In a single pole electric switch, in combination; master contact members and a detent normally positioned co-operatively therewith to prevent circuit breaking movement of said members, a thermo-dynamic device arranged co-operatively with resilient means when energized automatically to 10 open said contacts; a two-path, divided circuit in series with said master contacts including in one branch thereof said device, auxiliary contacts arranged in the other branch of said divided circuit, and common 15 manual controlling means for both said master and said auxiliary contacts.

13. In a single pole, electric switch, in combination; movable contact members and a detent normally positioned co-operatively therewith to prevent circuit breaking movement of said members, a thermo-dynamic device arranged co-operatively with resilient means when energized automatically to separate 20 said members, a circuit governed by said contact members, including in one branch thereof said device, auxiliary contacts for short-circuiting said device, and manual controlling means arranged to close both said members and said auxiliary contacts, and 25 upon subsequent actuation thereof to establish tension tending to separate said members and simultaneously to open said auxiliary contacts.

14. In a single pole, electric switch, in combination; master contact members and a detent normally positioned co-operatively therewith to prevent circuit breaking movement of said members, a thermo-dynamic device arranged co-operatively with resilient means when energized automatically to 30 open said contacts; a two-path divided circuit in series with said master contacts including in one branch thereof said device, auxiliary contacts arranged in the other 35 branch of said divided circuit, and manual controlling means arranged simultaneously to close both said master and said auxiliary contacts and upon subsequent actuation thereof to open said auxiliary contacts and 40 simultaneously to establish tension tending to open said master contacts.

15. In a rotary snap switch including an insulating base, stationary contact terminals mounted thereon and a rotatable contact device carrying a contact plate insulated therefrom and adapted in alternate stages of rotative progression conductively to bridge said terminals, in combination; a concentrically pivoted shaft having resilient 45 and detent connection with said device for manually imparting thereto a snap movement between stages, a bell crank lever pivoted to the base and normally positioned to intercept said device in its contact-bridging 50 position, a spring detent mounted be-

neath the insulating base and adapted to hold said shaft relatively advanced and separated under tension from said device when the latter is so intercepted, a thermostat and heating circuit therefor arranged when energized to actuate said lever and release said device, and an auxiliary current switch positioned beneath the insulating base and adapted to be operated by movement of said shaft, whereby said heating circuit may be 55 electrically energized when said device is tensioned for circuit breaking movement.

16. In an electric switch embodying a rotatable, contact-bridging structure for controlling the main circuit, said structure being 60 arranged to engage conductively with stationary circuit terminals in alternate stages of progressive rotation, and embodying also an actuating device for said structure, having tensioned connection thereto and stop 65 means positively preventing reverse movement of said structure and of said device between said stages, in combination; a movable detent normally arranged and positioned to intercept circuit-breaking movement of the said contact-bridging structure; a pawl detent operatively associated with the said actuating device thereby to hold the latter in position tensioning said structure for movement into a circuit breaking position; a thermostat normally positioned and formed co-operatively with said movable detent to prevent the release of said structure 70 from said movable detent; a normally inactive electric heating unit for the thermostat; and auxiliary switch means operably related to the said actuating device and electrically connected, when said device occupies its said tensioning position, to divert current through said electric heating unit, 75 thereby to energize operably the thermostat for causing a delayed release of said structure from said movable detent.

17. In an electric switch embodying a rotatable, contact-bridging structure for controlling the main current; said structure being arranged to engage conductively with stationary circuit terminals in alternate stages of progressive rotation, and embodying also an actuating device for said structure having tensioned connection thereto and stop means positively preventing reverse movement of said structure and of said device between said stages, in combination; a movable detent normally arranged and positioned to intercept circuit breaking movement of the said contact-bridging structure; a pawl detent operatively associated with the said actuating device thereby to hold the latter in position tensioning 80 said structure for movement into a circuit breaking position; a thermostat normally positioned and formed co-operatively with said movable detent to prevent the release of said structure from said movable detent; 85

- a normally, inactive electric heating unit for the thermostat; and an auxiliary contact bridging structure fixedly carried by said actuating device, and positioned thereon, 5 when said device occupies its said tensioning position, to divert current through said electric heating unit, thereby to energize operably the thermostat for causing a delayed release of said structure from said movable 10 detent.
18. In a current supplied electric circuit, the combination of a load, a cut-out, and a divided circuit all in series, said divided circuit containing in one branch thereof, a current 15 rent governed device operatively related to said cut-out, and said divided circuit containing in another branch thereof a current switching means for governing the supply of current to said device.
19. An electric switch embodying a progressively rotatable contact member; an actuator element mounted for progressive step-by-step rotative movement relatively in 20 advance of said members; a spring and detent connection between said member and

said element whereby rotative advances of said element relative to said member cause quick, follow-up rotative movements of said member, respectively to make and to break a circuit; a separate detent arranged to prevent said follow-up movement of said member from its circuit-making position when said element is rotatively advanced; means to hold said element so rotatively advanced, whereby said member is tensioned for circuit-breaking movement; and normally inactive, slow-acting, instrumentalities arranged to be operatively energized by the said rotative advance of said element, and thereby rendered operative to free said contact from said separate detent after a predetermined interval of time. 30 35
